UNITED STATES PATENT OFFICE.

SAMUEL W. POPEL, OF HARRISBURG, PENNSYLVANIA.

GUARD FOR ROOFS.

935,055.

Specification of Letters Patent. Patented Sept. 28, 1909.

Application filed March 8, 1909. Serial No. 482,148.

To all whom it may concern:

Be it known that I, SAMUEL W. POPEL, a citizen of the United States, and resident of Harrisburg, in the county of Dauphin and 5 State of Pennsylvania, have invented certain new and useful Improvements in Guards for Roofs, of which the following is a specification.

My invention relates to guards for roofs, 10 etc., adapted to be secured at the edges thereof or at any desired point, and my invention consists of certain brackets and rails supported and connected thereto, constructed and combined as fully set forth hereinafter 15 and as illustrated in the accompanying drawing, in which:

Figure 1 is an end view of part of a car roof illustrating my invention; Fig. 2 a side view in part section of one of the brackets 20 and one end of the rail; Fig. 3 a view illustrating the combination of different forms of brackets with the rail.

My improved guard consists of a plurality of brackets A, a cross-bar B, supported there- 25 by, and knobs C detachably connected to the ends of the cross-bar so as to hold it in place in the brackets.

As shown the brackets A are L-shaped and the vertical member or portion has an en- 30 largement a, in which is a socket or opening x, through which the cross-bar B is passed. The horizontal or base member b of each bracket has two faces, one of which may be placed upon a base, as in the bracket A', 35 Fig. 1, and with vertical openings for the passage of vertical screws or bolts c into the roof or other object to which the bracket is to be secured. The brackets may also have cross openings e, and side bearing faces so 40 that the said brackets may be secured by cross screws or bolts d to the sides of the rafters D of the roof. As shown the brackets are illustrated in connection with a railway car or other roof having the rafters D. The 45 horizontal members of the brackets are applied to the sides of the rafters and bolted thereto while the vertical members extend upward above the edge of the roof and therefore support the rail B at the extreme edge 50 as shown.

The rail is provided with threaded ends, or is otherwise adapted for the detachable application of the knobs C, which are put

in place after the rail has been passed through the brackets and thereby hold the 55 same firmly in its position. In some cases it is desirable to support the rail at points between the brackets A, and to further strengthen the same, and for this purpose I may employ supplemental brackets E which 60 have eyes or openings for the passage of the rail at one end and are straight so as to afford side faces, and with cross openings y for the passage of horizontal bolts into the joist or rafter or other member which 65 supports the bracket A. By this means the rail is held in place by the vertical screws or bolts c and the horizontal screws or bolts f.

I claim as my invention:

1. The combination with a roof and its 70 rafters D, of L-shaped brackets having eyes or openings at the ends of the vertical members, and transverse openings in the horizontal members adapted for the reception of bolts passing laterally into the rafters, and 75 rails passing through the said eyes and having knobs C detachably secured to the ends thereof.

2. The combination with a roof and its 80 rafters D, of L-shaped brackets having eyes or openings at the ends of the vertical members, and transverse openings in the horizontal members adapted for the reception of bolts passing laterally into the rafters and 85 rails passing through the said eyes and having knobs C detachably secured to the ends thereof, and intermediate straight brackets E having eyes in line with those of the other brackets and with transverse openings for receiving transverse bolts.

3. A bracket for guard rails having two members at about right angles to each other, one with a terminal eye or opening and the other with openings for the reception of securing bolts which extend substantially at 95 right angles to each other, whereby the bracket can be attached to a support with either its base or a side face in contact therewith as set forth.

In testimony whereof I affix my signature 100 in presence of two witnesses.

SAMUEL W. POPEL.

Witnesses:

CHARLES E. FOSTER,
ARTHUR L. BRYANT.
